Primary Examiner — Catherine Tuttle(74) *Attorney, Agent, or Firm* — Thompson Coburn LLP(57) **CLAIM**

The ornamental design for a hockey goalie slide board, as shown and described.

DESCRIPTION

FIG. 1 is a plan view of our new design for a hockey goalie slide board incorporating a graphic of the hockey goal crease area, a removable arcuate bumper, and four circular bumpers in the crease area;

FIG. 2 is a length-wise side view thereof;

FIG. 3 is a width-wise side view thereof, the opposing view being a mirror image thereof;

FIG. 4 is the length-wise side elevation view opposite to FIG. 2;

FIG. 5 is a plan view shown with the arcuate bumper removed for clarity;

FIG. 6 is an enlarged scale plan view of the region of FIG. 5 indicated by rectangle 6; and,

FIG. 7 is an enlarged scale plan view of the region of FIG. 5 indicated by rectangle 7.

The broken lines delineating the areas of enlargement in FIGS. 5-7 form no part of the claimed design.
